US00D806738S

(12) **United States Design Patent** (10) **Patent No.:** **US D806,738 S**
(45) **Date of Patent:** **** Jan. 2, 2018**

(54) **DISPLAY SCREEN OR PORTION THEREOF WITH GRAPHICAL USER INTERFACE**

(71) Applicant: **Apple Inc.**, Cupertino, CA (US)

(72) Inventors: **Matt Evans**, San Francisco, CA (US); **Gerhard Lengeling**, Los Altos, CA (US); **Alexander Harry Little**, Woodside, CA (US); **Mingxin Yu**, Palo Alto, CA (US)

(73) Assignee: **Apple Inc.**, Cupertino, CA (US)

(**) Term: **15 Years**

(21) Appl. No.: **29/601,413**

(22) Filed: **Apr. 21, 2017**

Related U.S. Application Data

(63) Continuation of application No. 29/564,844, filed on May 16, 2016, now Pat. No. Des. 788,805.

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The sole FIGURE shows a display screen or portion thereof with graphical user interface showing our new design.

The peripheral dashed broken lines illustrate a display screen or portion thereof and form no part of the claimed design.
